UNITED STATES PATENT OFFICE.

JOHN ALFRED COOPER, OF NOTTINGHAM, ENGLAND.

APPARATUS FOR TRAINING IN GUN-AIMING AND THE LIKE.

1,317,556.

Specification of Letters Patent. Patented Sept. 30, 1919.

Application filed July 16, 1919. Serial No. 311,392.

To all whom it may concern:

Be it known that I, JOHN ALFRED COOPER, a subject of the King of England, residing at Nottingham, England, have invented certain new and useful Improvements in Apparatus for Training in Gun-Aiming and the like, of which the following is a specification.

This invention relates to apparatus for training gunners and operators in gun aiming and the like, that is to say in aiming guns, directing searchlight-beams and similar directive operations on moving objects.

It is found desirable, especially for men engaged in laying guns upon aircraft, to give them practice in the use of the ring, or other sight on moving model targets, in order to enable them to follow an actual target, with the sight they have practised with, more readily and accurately than they otherwise would.

A primary object of this invention is to provide apparatus for use in practising aiming in which one or more model targets are mounted upon a rotatable carrier whose plane of rotation may be varied at will during its rotation.

Another object is to provide that one or more of the targets can be tilted about their pivotal axis during their rotation.

A further object is to provide that such tilting of the targets shall be caused automatically.

A still further object is to provide that the degree of tilt given to the targets shall vary more or less between some predetermined limits of angular movement of the carrier relatively to its support than between others.

An additional object is to provide that the one or more targets can be moved radially on the carrier during its rotation.

A further object is to provide that such radial movement shall be automatic.

A still further object is to provide apparatus for use in practising aiming in which the movements of an aeroplane flying in the air are more or less accurately simulated.

To these ends, the invention consists in the construction, arrangement and combination of parts described hereinafter and pointed out in the claims.

One embodiment of the invention is illustrated by way of example, in the accompanying drawings, wherein:

55 Figure 1 is a front elevation, and

Fig. 2 is a side elevation of one form of apparatus according to the invention;

Fig. 3 is a view similar to Fig. 1 but from the rear showing the moving parts of the apparatus in various positions, and 60

Fig. 4 is a vertical sectional view of a detail of construction on a larger scale than that of Figs. 1-3;

Figs. 5 and 6 are enlarged side and end elevations, respectively, of another detail of 65 construction.

Like reference letters designate like parts throughout the several views.

Referring to the drawing, the apparatus comprises a carrier A rotatably mounted on 70 a bracket or head B, which latter is carried upon an upright support C and is oscillatable thereupon about an axis C¹. The head or bracket B is constructed in the form of a forked member whose limbs B¹ embrace the 75 upright C and are engaged therewith by pivot-pins C². In order to give to the head the required inclination about the said spindle, a bevel-wheel D is secured, co-axially with the pivots C², upon one fork-limb B¹, and is operated by means of a bevel-wheel D¹ which receives rotation from a hand-operated worm and worm-wheel device E at the lower end of the upright C and connected with the bevel-wheel D¹ through 85 a spindle D².

Upon the other fork-limb is mounted a bevel-wheel F, co-axial with, but free upon, the pivots C² and engaging with two bevel-wheels F¹, F², one above it and one below it, 90 whose axes of rotation are at right-angles to that of the said pivots. The lower wheel F¹ of these two is driven by hand-operated worm-wheel gear E¹ and the upper F² transmits its rotation through a short shaft F³ 95 to a spur-wheel F⁴ engaging with a spur-wheel G. The shaft F³ carrying the bevel-wheel F² and spur-wheel F⁴ runs in bearings F⁵ secured to the head. By this means as the head is made to oscillate about its pivots C², the shaft F³ is maintained in constant driving engagement with its hand-operated gear E¹.

The carrier A comprises a central double tubular shaft A¹, A² (see also Fig. 4) rotatably mounted co-axially on the bracket or head B. A guide-tube B² formed on the head B extends into the annular space between the tubular portions A¹, A² to guide and support them. The spur-wheel G is 110 formed on the lower end of the tubular stem A¹ of the carrier. Supported at right-angles to the length of the stem of the carrier are two outwardly extending arms J,

J¹. At their extremities these arms each support, upon pivots K¹, a model aeroplane K, and to an arm K² upon each aeroplane is secured one end of a flexible tie L which extends to the outer end of the tubular shaft A¹, A² and passes down it to a plunger M engaged with the inner portion of the shaft by a sliding feather M² so as to be non-rotatable in relation thereto but slidable axially along it. The plunger M is further tied through a swivel-joint M¹ to the support C. As, therefore, the head B is swiveled about its pivots C², the plunger M is caused to slide in the tubular stem of the carrier A and, through the ties L, tilts the aeroplanes K about their pivots K¹.

If desired, the outer portions J¹ may be telescopically mounted in their inner portions, as shown at the left-hand side of Fig. 20. 1. In this construction the outer telescopic member is pressed outward by a spring Q and carries at its inner end a finger J². A cam-ring P fast on the head B has its operative face surrounding the axis of the carrier A, and a bracket R, mounted on the arm J carries a rocker S. The finger J² bears against one end of this rocker, the other end of which bears against and is controlled by the cam P.

30. In use, the carrier is maintained in rotation by the hand-operated gears E¹ so causing the aeroplanes K to rotate in a circular path. Operation of the gear E causes the head B to be swung about its pivots C², and 35 so tilts the plane of their path. At the same time the tilting of the head causes the aeroplanes to change their apparent banking, and so more or less to simulate the action of an aeroplane. In order that 40 this may be more or less accurately simulated, the ties L by which this motion is produced may be wrapped around a drum, pulley, cam, eccentric or other rotary member or members of cam-contour suitably interposed in their path.

Such a rotary member O in the form of a pulley is shown in Figs. 5 and 6 and is indicated in dotted lines in Fig. 1. The grooved pulley O is mounted eccentrically 50 on a spindle O¹ journaled in a pedestal O² carried by a stay wire J³. Fast on the spindle O¹ is a pulley O³ to which is attached, and around which is wrapped, a flexible tie L¹ whose other end is secured to the plunger M. The flexible tie L extending from the arm K² is secured to a point on the periphery of the eccentric O, so that the degree of tilt given to the aeroplane is not the same for every angular movement of 55 the pulley O, but depends upon the angular position of the pulley at the moment, as will readily be understood.

When a cam as indicated at P is employed in conjunction with telescopic arms, 60 the result is that as the arms J, J¹ revolve,

the targets K move radially in and out from the center of their rotation so long as the fingers J² engage the cam P.

What I claim as my invention and desire to secure by Letters Patent is:—

1. In apparatus for use in practising aiming, the combination with a support, of a carrier mounted thereon to rotate in various planes of rotation, and a model target mounted on the carrier.

2. In apparatus for use in practising aiming, the combination with a support, of a rotatable carrier mounted to rock thereon about a horizontal axis of rotation, and a model target mounted on the carrier.

3. In apparatus for use in practising aiming, the combination with a support, of a carrier mounted thereon to rotate in various planes of rotation, means for rotating the carrier, and a model target mounted on the carrier.

4. In apparatus for use in practising aiming, the combination with a support, of a rotatable carrier mounted to rock thereon, means for rocking the carrier on its support, and a model target mounted on the carrier.

5. In apparatus for use in practising aiming, the combination with a support, of a rotatable carrier mounted to rock thereon, means for rotating and means for rocking the carrier on its support, and a model target mounted on the carrier.

6. In apparatus for use in practising aiming, the combination with a support, of a rotatable carrier mounted to rock thereon, a target pivotally mounted on the carrier, means for rotating and means for rocking the carrier, and means for automatically tilting said target about its pivot when the carrier is rocked on its support.

7. In apparatus for use in practising aiming, the combination with a support, of a carrier mounted to rotate thereon, a target movable radially on the carrier towards and away from its axis of rotation, means for rotating the carrier, and means for radially moving the target during the rotation of the carrier.

8. In apparatus for use in practising aiming, the combination with a support, of a carrier mounted to rotate thereon, a target movable radially on the carrier toward and away from its axis of rotation, means for rotating the carrier, and means for automatically moving the target radially during the rotation of the carrier.

9. In apparatus for use in practising aiming, the combination with a support, of a rotatable carrier mounted to rock thereon, a target movable radially on the carrier toward and away from its axis of rotation, means for rotating and means for simultaneously rocking the carrier, and means for radially moving the target during the rotation of the carrier.

10. In apparatus for use in practising aiming, the combination with a support, of a rotatable carrier mounted to rock thereon, a target pivotally mounted on the carrier and radially movable thereon toward and away from its axis of rotation, means for rotating and means for simultaneously rocking the carrier, means for automatically tilting said target about its pivot when the carrier is rocked on its support, and means for radially moving the target during the rotation of the carrier.
11. In apparatus for use in practising aiming, the combination with a support, of a bracket mounted to rock about an axis thereon, a carrier mounted on said bracket to rotate about an axis at right-angles to the said former axis, toothed-wheel gearing comprising a gear-wheel co-axial with the axis of rotation of the brackets and secured to the bracket for rocking the same, and toothed-wheel gearing operatively connected with the carrier and comprising a gear-wheel co-axial with the axis of rotation of the bracket, for rotating the carrier.
12. In apparatus for use in practising aiming, the combination with a support, of a rotatable carrier mounted to rock thereon, means for rotating and means for rocking the carrier on its support, a target pivotally mounted on the carrier, an arm on the target for tilting the same about its pivotal axis, a member operatively connected to the support and to the carrier and movable relatively to the latter when the same is rocked, and a tie having one end attached to said arm and its other end attached to said member.
13. In apparatus for use in practising aiming, the combination with a support, of a rotatable carrier having a tubular stem mounted to rock thereon, means for rotating and means for rocking the carrier on its support, a target pivotally mounted on the carrier, an arm on the target for tilting the same about its pivotal axis, a plunger slideable axially in and rotatable with the stem of the carrier, means pivotally connecting the plunger with a part of the support on the side of the fulcrum of the carrier remote from the latter, and a tie having one end attached to said arm and its other end attached to said plunger.
14. In apparatus for use in practising aiming, the combination with a support, of a rotatable carrier mounted to rock thereon, means for rotating the carrier on its support, a cam-ring mounted on the support with its operative face surrounding the axis of rotation of the carrier, said carrier having a radial telescopic arm, a target mounted on the outer telescopic part of the said arm, and a spring-pressed finger carried by the outer telescopic part of the arm and controlled by said cam-ring.
15. In apparatus for use in practising aiming, the combination with a support, of a carrier mounted thereon to rotate in various planes of rotation, a model target mounted on the carrier, and means for tilting the target more relatively to the carrier at some predetermined planes of rotation of the carrier than at others.
16. In apparatus for use in practising aiming, the combination with a support, of a rotatable carrier mounted to rock thereon, a target pivotally mounted on the carrier, means for rotating and means for rocking the carrier, and tilting means for automatically tilting said target through a greater angle about its pivot when the carrier is rocked through some parts of its angular travel than through other parts.

In testimony whereof I affix my signature.

JOHN ALFRED COOPER.
